BREECH-LOADING ORDNANCE.

1,289,690.

Specification of Letters Patent.

Patented Dec. 31, 1918.

Application filed April 13, 1915. Serial No. 21,122.

To all whom it may concern:

Be it known that we, Sir ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to Breech-Loading Ordnance, of which the following is a specification.

This invention relates to breech loading ordnance having breech mechanism of the sliding or wedge type, in which the breech block is operated by a crank carried by or connected to the axis pin of the actuating hand lever and in which the striker is cocked by a lever between which and the operating crank an actuating member or lever is interposed.

According to the present invention the interposed actuating member or lever is so constructed and arranged as to be capable of independent manual movement to recock the striker so that this member serves both to cock and to re-cock the striker. The said actuating member may comprise two arms one (termed the intermediate cocking arm) arranged in contact with a projection, such as a roller, on the crank, and the other (termed the cocking arm) arranged in contact with a projection on the cocking lever and provided with a re-cocking lanyard loop or other operating part or arranged in contact with a re-cocking lever so that movement of the latter effects the re-cocking operation through the said actuating member. The said intermediate cocking arm may be provided with an extension which serves to coöperate with a part moving with the crank during the opening and closing of the breech to hold the cocking lever in its cocked position after the projection on the crank has moved out of contact with the intermediate cocking arm during the opening of the breech mechanism and until the said projection has reengaged with the intermediate cocking arm during the closing of the breech mechanism; by these means the cocking lever is prevented from moving forward if the sear for any reason does not hold the said lever in its cocked position.

In order that the said invention may be clearly understood and readily carried into effect, we will describe the same more fully

with reference to the accompanying drawings, in which:

Figures 1, 2 and 3 are respectively a rear elevation, a side elevation, and a plan showing the breech end of a gun provided with a constructional form of our improvements.

Fig. 4 is a section taken approximately on the line 1, 1 of Fig. 1.

Figs. 5, 6 and 7 are views similar to Figs. 1, 2 and 3 but with parts thereof in section to show more clearly this constructional form of our improvements.

Fig. 8 is a sectional plan showing the aforesaid extension on the intermediate cocking arm coöperating with a part moving with the crank.

Figs. 9, 10 and 11 are views similar to Figs. 5, 6 and 7 showing another constructional form of our improvements.

Figs. 12 and 13 are respectively a sectional rear elevation and a plan showing on an enlarged scale certain details of Figs. 10 and 11.

In these figures A is the breech end of the gun. B is the sliding breech block. B' is the breech actuating hand lever and B² its spindle. B³ is the operating crank, and B⁴ the cocking lever which in the example shown also serves as a firing lever. C, C' represent the two arms of the aforesaid actuating member or lever and C² is their connecting vertical pivot, the intermediate cocking arm C lying as aforesaid in contact with a roller b³ on the operating crank, and the cocking arm C' lying in contact with a projection b⁴ on the cocking and firing lever. C represents the aforesaid extension on the intermediate cocking arm C for coöperating with a part moving with the crank.

The operating crank B³ in the examples shown, is pivoted at B^{3x} in the breech ring and carries a cross-head b^{3x} engaging in a groove b which is formed in the top surface of the breech block parallel to the axis of the gun.

In the constructional form of the invention shown by Figs. 1 to 8, the vertical pivot C² carrying the intermediate cocking arm C and the cocking arm C' is arranged at the rear part of the breech block in such a position that a lanyard loop C'x (Figs. 5 and 6) can be formed on the cocking arm C' to enable the re-cocking operation to be effected; in this construction the crank axis pin

B^{3x} is arranged in front of the said vertical pivot. When the breech actuating hand lever B' is angularly displaced to open the breech, the operating crank is moved to an anti-clockwise direction (Fig. 7) and the roller b^3 co-operates with the intermediate cocking arm C to rock the pivot C^2 and thereby cock the striker through the intermediary of the cocking arm C' and the cocking and firing lever B^4 . When the operating crank assumes the position shown by Fig 8 during the opening of the breech, the extension c on the intermediate cocking lever C lies against the aforesaid block b^{3x} on the operating crank and the cocking and firing lever B^4 is retained in its cocked position even if the sear is no longer holding it cocked; this retaining of the cocking and firing lever only ceases when the breech block is assuming its closed and locked position in which condition the roller b^3 which had during the opening movement been carried out of engagement with the intermediate cocking arm C , resumes its engagement therewith.

This construction is particularly applicable to semi-automatic gear for opening the breech during the run out movement of the gun and to enable this to be effected the crank axis pin B^{3x} carries a toothed segment B'^x meshing with a pinion B^{2x} on the hand lever spindle B^2 which is arranged in front of the crank axis pin. The lower end of this spindle terminates in a cam B^{4x} which engages with a pawl on the cradle when the gun runs out after recoil. Keyed to the upper end of the spindle is another pinion b^{2x} (Figs. 2 and 3) engaging with a rack B^x (Fig. 3) slidably mounted in the hand lever B' . The breech closing spring B^{xx} is interposed between the rack and the front end of the hand lever casing. In this construction the gun carries a spring plunger or bolt b^x which when the gun is working on the semi-automatic principle locks the hand lever to B' to the gun but which can be moved to its disengaged position to enable the breech mechanism to be manually operated by the hand lever B' when desired.

In the constructional form of the invention shown by Figs. 9 to 11, the position of the crank axis pin B^{3x} and the vertical pivot C^2 of the cocking and intermediate cocking arms C' , C is reversed, that is to say the said pivot is arranged in front of the crank axis pin. In this case the re-cocking operation is effected by a separate re-cocking lever C^x pivoted at c^x in the breech block, this lever co-operating with the cocking arm C' . In other respects this construction is substantially the same as that illustrated by Figs. 1 to 8 except that in Figs. 9 to 11 the mechanism is shown applied to a quick firing gun in which the breech is opened by hand, the breech actuating hand lever being

mounted on the upper end of the crank axis pin B^{3x} and being moved in a clockwise direction to open the breech.

What we claim and desire to secure by Letters Patent of the United States is:—

1. In breech mechanism the combination with the operating mechanism of the breech block, the striker and the cocking lever thereof, of a member interposed between said actuating mechanism and the lever for cocking the striker during the opening of the breech, said member being capable of independent movement to re-cock the striker without necessitating the opening of the breech.

2. In breech mechanism the combination with the operating mechanism of the breech block, the striker and the cocking and firing lever thereof, of a member interposed between said actuating mechanism and the cocking and firing lever for cocking the striker during the opening of the breech, said member being capable of independent movement to re-cock the striker without necessitating the opening of the breech.

3. In sliding block breech mechanism, the combination with the operating mechanism of the breech block, the striker and the cocking lever thereof, of a member interposed between said actuating mechanism and the lever for cocking the striker during the opening of the breech, said member being capable of independent movement to re-cock the striker without necessitating the opening of the breech.

4. In sliding block breech mechanism, the combination with the operating crank of the breech block, the striker and the cocking lever thereof, of a member interposed between said operating crank and the lever for cocking the striker during the opening of the breech, said member being capable of independent movement to re-cock the striker without necessitating the opening of the breech.

5. In breech mechanism, the combination with the operating mechanism of the breech block, the striker and the cocking lever thereof, of a member interposed between said actuating mechanism and the lever for cocking the striker during the opening of the breech and manually operated means for displacing said member to re-cock the striker without necessitating the opening of the breech.

6. In breech mechanism, the combination with the operating mechanism of the breech block, the striker, and the cocking lever thereof, of a lever interposed between said actuating mechanism and the cocking lever for cocking the striker during the opening of the breech, said interposed lever being capable of independent movement to re-cock the striker without necessitating the opening of the breech.

7. In sliding block breech mechanism, the

- combination with the operating crank of the breech block, the striker and the cocking lever thereof, of a pivot pin carried by the breech block, an arm on said pivot pin for 5 engaging with said crank, a second arm on said pivot pin for engaging with said cocking lever, and means for operating said arms to re-cock the striker without necessitating the opening of the breech.
- 10 8. In sliding block breech mechanism, the combination with the operating crank of the breech block, the striker and the cocking and firing lever engaging with said striker, of a vertical pivot pin carried by the breech block, 15 an arm on the upper part of said pivot pin for engaging with said crank, a second arm on the lower part of said pivot pin for engaging with said cocking and firing lever, and means for operating said arms to re-cock 20 the striker without necessitating the opening of the breech.
9. In sliding block breech mechanism, the combination with the operating crank of the breech block, the striker and the cocking 25 lever thereof, of a pivot pin carried by the breech block, an arm on said pivot pin for engaging with said crank, a second arm on said pivot pin for engaging with said cocking lever, and a re-cocking extension on said 30 second arm.
10. In breech mechanism, the combination with the operating mechanism of the breech block, the striker and the cocking lever thereof, of a member interposed between
- said actuating mechanism and the lever for 35 cocking the striker during the opening of the breech and means for retaining said member in its cocked position while the breech is open.
11. In sliding block breech mechanism, 40 the combination with the operating crank of the breech block, the striker and the cocking lever thereof, of a member interposed between said crank and the lever for cocking the striker during the opening of the breech 45 and means carried by the crank for retaining the member in its cocked position when the crank moves out of engagement with said member.
12. In sliding block breech mechanism, the 50 combination with the operating crank of the breech block, the striker and the cocking lever thereof, of a member interposed between said crank and lever for cocking the striker during the opening of the breech, an 55 arm on said member, and means carried by the crank for coöoperating with said arm to retain the member in its cocked position during the time that the crank is out of engagement with said member.

In testimony whereof we affix our signatures in the presence of two witnesses.

ARTHUR TREVOR DAWSON.
GEORGE THOMAS BUCKHAM.
